UNITED STATES PATENT OFFICE.

HARRY C. NEWMAN, OF LOS ANGELES, CALIFORNIA, ASSIGNOR OF ONE-THIRD TO
H. D. EBERLE AND ONE-THIRD TO SPENCER C. ROGERS, BOTH OF LOS ANGELES,
CALIFORNIA.

JACK.

Application filed June 28, 1921. Serial No. 481,136.

To all whom it may concern:

Be it known that I, HARRY C. NEWMAN, a citizen of the United States, residing at Los Angeles, in the county of Los Angeles and State of California, have invented a new and useful Jack, of which the following is a specification.

My invention relates to jacks and is particularly applicable to jacks which are used 10 to raise the axles of automobiles and trucks.

It further relates to jacks operating on the principle of hydraulic pressure, oil being used, however, as the pressure matter.

The principal object of the invention is 15 to provide a jack which will have a very great mechanical strength and one in which leakage of oil will be almost entirely prevented.

A further object is to make a jack which 20 can be very cheaply constructed of relatively inexpensive materials.

Further objects and advantage will be made evident hereinafter.

Referring to the drawings which are for 25 illustrative purposes only,

Fig. 1 is a cross section through a preferred embodiment of my invention.

Fig. 2 is a side elevation thereof.

Fig. 3 is a section on a plane represented 30 by the line 3—3 of Fig. 1.

Fig. 4 is a partial section through the by-pass valve.

Fig. 5 is an end view of the handle.

Fig. 6 is an enlarged view showing the 35 large piston in longitudinal section taken on line 6—6 of Fig. 7, and the small piston in elevation.

Fig. 7 is a cross section of the large piston taken on line 7—7 of Fig. 6.

In the form of the invention shown, I 40 provide a base 11 which is preferably formed of cast iron and in which is secured a reservoir casting 12, this casting being threaded at 13 into a central recess 45 formed in the base 11. The casting 12 consists of an inner wall 14 in the form of a cylinder and an outer wall 15 which walls are separated by an oil space 16, but are formed integral with each other at their 50 upper ends. A lap joint 17 is provided where the wall 15 joins to the base, the base being provided with a lip 18 fitting inside the wall 15 and making an oil tight joint therewith. Threaded in a cavity 19 in the 55 base 11 is a pump cylinder 20 in which a

plunger 21 is free to reciprocate, this plunger being pivoted on a pin 22 in a lever 23 which is pivoted upon a pin 24 carried in a link 25 which is in turn pivoted on a pin 26 carried on the casting 12. The lever 23 is provided with a cylindrical end 27 having a pin 28 therein, this end being engaged by a handle 29 which has the form shown in Fig. 5. The handle 29 consists of a hollow tube having a bayonet type slot 30 formed 60 therein.

The lower end of the cavity 20 communicates with the lower end of the cavity 13 through a cored passage 35, a ball 36 being seated in this passage in such a manner as to allow oil to pass from the passage 35 into the cylinder 37 formed inside the wall 14, but to prevent any liquid from passing into the passage 35 from the cylinder 37, the ball 36 is held in place with a screw 70 plug 38. A ball 40 held upwardly by a spring 41 against a seat formed on a plug 42 closes a passage between the space 16 and the passage 35 in such a manner that liquid may pass from the space 16 into the passage 35, but is prevented by the ball 40 from passing from the passage 35 into the space 16. A by-pass passage 45 is provided in the base 11 connecting the space 16 with the cylinder 37, this passage being closed by 75 the end 46 of a threaded stem 47 which is provided on its outer end with a pin 48 which may be engaged by the handle 29.

The inner surface of the wall 14 is machined to form a cylinder and a large piston 50 is free to slide therein, being provided with a cup leather 51 secured by a nut 52. The nut 52 has an opening 53 therein so that oil may pass from the cylinder 37 into the space 54 inside the large piston 50. The 80 large piston 50 is provided with longitudinal 55 grooves formed on the outer surface thereof, these grooves extending from a point 56 to a point 57. Small holes 58 are drilled through the large piston 50 communicating with grooves 55. A brass tube 59 is threaded at 60 to the large piston 50 and extends down to a point 61. A stuffing box consisting of packing 65 and a nut 66 makes a tight joint between the upper portion of 85 the member 12 and the tube 59, holes 67 being drilled in the wall 14. Sliding in the cavity 54 is a small piston 70 which carries a stirrup 71 on its upper end upon 90 which the load to be lifted is supported. 105

A cup leather 72 is carried on the lower end of the piston 70.

The method of operation of the invention is as follows:

5 The spaces 54 and 16 and the cylinder 37 are filled with oil with the piston 50 and the piston 70 at their lowest position as shown in Fig. 2. The passage 45 is closed by the member 46. The plunger 21 is re-
10 ciprocated by means of the handle 29 each up-stroke taking oil from the space 16 past the ball 40 and each down-stroke forcing this oil past the ball 36 into the cylinder 37. This builds up a fluid pressure in the cylin-
15 der 37 and space 54 and this pressure ex-
erted upwardly upon the lower end of the large piston 50 tends to raise same, the piston 70 remaining in its lower position in the piston 50 but being carried upwardly
20 thereby. Any oil which may leak past the cup leather 51 passes through the hole 67 into the space 16. Any oil leaking past the cup leather 72 passes through the holes 58 through the grooves 55 and through the
25 holes 67 into the space 16. The upward movement of the piston 50 continues until the shoulder 100 strikes against a washer 101 secured below the packing 65. If pres-
30 sure continues to be exerted, the inner piston 70 starts to rise and continues to rise until the cup leather 55 passes a series of ports 103 formed in the member 50. As soon as this occurs, the pressure relieves itself through these ports into the grooves 55 and
35 back through the holes 67 into the reser-
voir 16. It will thus be seen that the jack operates by moving the piston 50 upwardly to the limit of its movement, and that it thereafter operates by raising the piston 70
40 to the limit of its movement. This gives a very long stroke for a short jack and also gives a very great power due to the fact that the leverage is greatly multiplied due to the small area of the plunger 21 as com-
45 pared to the areas of the pistons 50 and 70 and also due to the long leverage provided by the handle 29.

Whenever it is desired to lower the weight, this can be done by turning the

screw 47 and allowing oil to leak back into 50 the space 16 from the cylinder 37 through the passage 45. This leakage of the oil can be accurately regulated so the load comes down slowly and this downward movement of the load can be instantly arrested by 55 closing the passage 45 of the member 46.

Particular attention is called to the construction of the member 12 which is extremely rigid, the threads holding it solidly down into the base 11 and the member 12 60 being further supported at the point 17. The member 12 is in the form of a casting which is provided with stiffening ribs 110 between the walls 14 and 15, these stiffening ribs making the member 12 very rigid. As 65 the cavity 16 is cored out, the member 12 is extremely cheap to make and renders this type of jack commercially feasible.

I claim as my invention:

A jack including: a cylinder closed at its 70 lower end and having ports in its wall near its upper end; a hollow piston including a head on its lower end slidable in said cylinder in fluid-tight contact therewith, said piston having a port in its head and ports 75 in its upper end; a stuffing box on the upper end of said cylinder through which said piston extends; a tube surrounding said piston and extending downwardly through said stuffing box in fluid-tight contact there- 80 with, the upper end of said tube being se-
cured to the upper end of said piston, there being a fluid return space formed between said piston and said tube, the upper end of 85 said space communicating with said ports in the upper end of said piston, said return space being in open communication with the interior of said cylinder at a point above said piston head and below said stuffing box; a second piston slidable inside said hollow 90 piston; a piston rod secured to said second piston projecting upwardly outside said first piston; and a closure about said piston rod at the upper end of said first piston.

In testimony whereof, I have hereunto set 95 my hand at Los Angeles, California, this 21st day of June, 1921.

HARRY C. NEWMAN.
